UNITED STATES PATENT OFFICE.

WILLIAM CORRY, OF CINCINNATI, OHIO.

FIREPROOF SAFE.

SPECIFICATION forming part of Letters Patent No. 681,105, dated August 20, 1901.

Application filed June 15, 1901. Serial No. 64,651. (No model.)

To all whom it may concern:

Be it known that I, WILLIAM CORRY, a citizen of the United States of America, and a resident of Cincinnati, in the county of 5 Hamilton and State of Ohio, have invented certain new and useful Improvements in Fireproof Safes, of which the following is a specification.

The object of my invention is a fireproof safe the door and door-frames of which will not bulge from the expansion of the fireproof filling. This object is attained by the means described in the annexed specification and illustrated in the accompanying drawing, in 15 which the figure is a horizontal cross-section of a safe embodying my invention.

Referring to the parts, outer shell A consists of a front and a rear frame made of angle-bars $a a'$, to which are secured plates a^2 , forming the top, bottom, and sides of said shell. To angle-bar a is secured the casting forming door-jamb B, to the inner edge of which is secured inner shell C. All of these parts are of ordinary construction and need 25 not therefore be more specifically described. Front plate d , inwardly-projecting casting d' , and cap-plate d^2 of the door are likewise of ordinary construction.

It has been the custom to fill in the space 30 inclosed by the inner shell, the outer shell, and the door-jamb of the safe and the space upon the interior of the door with fireproof cement. It frequently happens, even though great care be exercised in selecting the cement, that in setting it expands and presses 35 outward in the shell of the safe against the door-jamb and in the door against the inwardly-projecting casting, causing them to swell outward, so that the door binds against 40 its jamb. To obviate this defect, before the cement is applied I place sheets E of material such as sheet metal, asbestos, papier-mâché, &c., between the inner and outer shells at a 45 short distance inward from the door-jamb and running substantially parallel to the

sides, top, and bottom, respectively, thereof, securing each sheet by screws or in any other suitable manner at one of its ends to the inner shell and at the other end to the outer shell. Similarly within the door I secure a 50 sheet E' parallel to each side of casting d' , leaving a space between it and the casting. The fireproof cement in its plastic state is then put into the spaces between the outer and the inner shells of the body of the safe and 55 into the interior of the door, sheets E keeping it back from the jamb and from casting d' , so as to leave an open space surrounding each, which gives room for any expansion the cement may undergo in setting, so that the 60 jamb and the door are not affected thereby. While this space left about the jamb and the door overcomes the defect due to expansion of the filling, it does not affect the fireproof 65 character of the safe.

What I claim is—

1. A fireproof safe having a space left between the cement filling and the door-jamb, to allow of an expansion in the cement in setting without affecting the jamb. 70
2. A fireproof safe within the door of which a space is left between the fireproof filling and the casting forming the periphery, for an expansion in the cement in setting.
3. In a fireproof safe a sheet of material 75 between and secured to the inner and outer shell thereof adjacent to the door-jamb and surrounding the same to keep the fireproof filling back from the door-jamb so that the filling in setting may expand without affect- 80 ing the jamb.
4. A fireproof safe between the door-jamb and fireproof filling of which and within the door of which between the periphery of the door and the fireproof filling spaces are left 85 for the expansion of the filling in setting.

WILLIAM CORRY.
